Primary Examiner — John Windmuller(74) *Attorney, Agent, or Firm* — Volpe and Koenig, P.C.(57) **CLAIM**

The ornamental design for a cotter pin, as shown and described.

DESCRIPTION

FIG. 1 is a perspective view of a cotter pin according to our invention;

FIG. 2 is a front elevation thereof;

FIG. 3 is a rear elevation thereof;

FIG. 4 is right side elevation thereof;

FIG. 5 is left side elevation thereof;

FIG. 6 is a top plan view thereof;

FIG. 7 is a bottom plan view thereof;

FIG. 8 is a perspective view of the cotter pin according to our invention in the use environment; and,

FIG. 9 is a perspective view of a prior art cotter pin in the use environment.

The broken line showings of castle nuts are for the purpose of illustrating environment and form no part of the claimed design.

1 Claim, 6 Drawing Sheets(56)
